[57] CLAIM

The ornamental design for a housing for a data processor, as shown and described.

DESCRIPTION

FIG. 1 is a top, front, and right-side perspective view of a housing for a data processor showing our new design; FIG. 2 is a top, front, and left-side perspective view thereof;

FIG. 3 is a top, front, and right-side perspective view of a second embodiment of our new design;

FIG. 4 is a top, front, and left-side perspective view thereof;

FIG. 5 is a front elevational view of the first embodiment of our new design;

FIG. 6 is a top plan view common to both embodiments.

FIG.
1
